HANS A. CHRISTIANSEN AND LESLIE E. MERRICK, OF AGAR, SOUTH DAKOTA.

BROODER.

Application filed July 23, 1926. Serial No. 125,499.

In the artificial hatching of chickens a brooder is an essential adjunct and it is of vital importance that a device of this nature maintain an even temperature and insure a supply of fresh air without subjecting the chicks to air drafts which is detrimental. The invention further aims to provide a brooder which admits of ready inspection of the brood and the admission of light and which may be easily kept clean.

While the drawings illustrate a preferred embodiment of the invention, it is to be understood that in adapting the means to meet specific needs and requirements the design may be varied and such other changes in the minor details of construction may be resorted to within the scope of the invention as claimed, without departing from the spirit thereof.

For a full understanding of the invention and the merits thereof, reference is to be had to the following description and the drawings hereto attached, in which,

Figure 1 is a perspective view of a brooder embodying the invention, provided with a roof when intended for out-door use.

Figure 2 is a vertical transverse section of the brooder, on the line 2—2 of Figure 3, looking rearward, as indicated by the arrows, the roof being omitted, and

Figure 3 is a vertical, central longitudinal sectional view of the brooder, the roof being omitted.

Corresponding and like parts are referred to in the following description and designated in the several views of the drawings by like reference characters.

The brooder comprises similar upper and lower chambers 1 and 2 which, in the preferable construction, are formed from sheet metal. These chambers 1 and 2 are of like dimensions and are placed one upon the other and are hingedly connected, as indicated at 3, whereby the upper chamber 1 may be raised when required. The lower chamber 2 is preferably open at the bottom and top and is provided in its back wall with an opening to which is fitted a door 4, the same being hinged at its top to normally maintain a closed position. A lamp 5 is located in the chamber 2 and is removable through the opening closed by means of the door 4. The part 2 constitutes the heating chamber in contradistinction to the part 1 which forms the brood chamber.

The brood chamber 1 is closed by a bottom 6 which is preferably of sheet metal and in the center of which is formed an opening 7. A top 8 extends over the chamber 1 and is hinged thereto, as indicated at 9. Openings 10 are formed in the top 8 and enclosing walls of the chamber 1 for ventilation to admit fresh air and provide an escape for vitiated air.

A drum 11 is secured to the bottom 6 opposite the opening 7 and a vent pipe 12 extends from the top thereof through the top 8. The hot air and gases from the lamp 5 pass from the heating chamber 2 through the opening 7 into the drum 11, thence through the vent pipe 12 into the atmosphere. A plate 13 connected to the bottom 6 and spaced therefrom acts as a spreader and the hot air and gases striking the lower side of the plate 13 are deflected laterally in all directions and pass around the outer edges of the plate, thence along the top side of the plate 13 and out through the opening 7. In this manner the bottom 6 of the brood chamber 1 is heated throughout its extent. Bolts 14 connect the spreader plate 13 to the bottom 6 and spacers mounted upon the bolts 14 maintain the plate 13 a fixed distance from the bottom 6. A bed 16 of sand or other suitable granular material is placed upon the bottom 6 to any desired depth and this bed surrounds the lower portion of the drum 11 and operates to uniformly distribute the heat. At stated intervals the top portion of the bed 16 may be removed and if desired may be replaced by a like amount of fresh material. In this way the brooder is rendered sanitary and may be easily kept clean.

When the brooder is located out doors it is provided with a roof 17 to shed rain and to afford protection. The roof 17 is provided with depending straps 18 adapted to engage loops 19 upon the outer side of the brood chamber, pins 20 passing through the parts to retain the roof in place. Obviously, when the brooder is located in doors the roof 17 is not necessary and is dispensed with. A runway 21 extends from the bottom of the brood chamber 1 to the ground and is provided upon its top side with cleats or lags to enable the chicks to obtain a sure footing both when leaving and entering the brooder. A door 22 closes an opening in the lower portion of the front of the brood

chamber and is hinged at the top to normally maintain a closed position and is free to swing inwardly and outwardly so that the chicks may enter or leave the brood chamber 5 without hindrance.

The brooder may be used with equal advantage in-doors or out-doors but when arranged in the open, it is essential that the roof 17 may be employed. The brood chamber 10 is maintained at the required temperature by proper adjustment of the lamp 5, said temperature being ascertained in the usual way by means of a thermometer, not shown, associated with the device. Access 15 to the lamp 5 is readily had through the opening closed by the door 4. The brood may be inspected by opening the top 8 and when sunshine is to be admitted into the brood chamber the top 8 may be propped 20 open, as will be readily understood. The drum 11 may be connected to the bottom 6 in any preferred way, as by being soldered thereto. The brood chamber may be readily cleaned by opening the top 8 and swinging 25 said chamber upon the hinges 3 whereby to discharge the material forming the bed 16.

Having thus described the invention, we claim:

1. A brooder comprising separable upper 30 and lower chambers, a heater in the lower chamber, the upper chamber having a bot-

tom which extends over and closes the top of the lower chamber and said bottom having a centrally disposed opening, a plate attached to the bottom of the upper chamber and spaced therefrom, and terminating at its edges a short distance from the enclosing walls of the lower chamber and a drum supported upon the bottom of the upper chamber in line with the opening therein and having a vent pipe extending from the top thereof through the top of the upper chamber. 35

2. A brooder comprising separable upper and lower chambers, the upper chamber having a bottom extending over and closing the top of the lower chamber, and formed with an opening, a heater in the lower chamber, a spreader above the heater for deflecting the heat in all directions and suspended 40 from the bottom of the upper chamber, a granular bed placed upon the bottom of the upper chamber and a drum having its lower end passing through the said granular bed and supported upon the bottom of the upper chamber in line with the opening therein and having a vent pipe extending therefrom through the top of the chamber. 45

In testimony whereof we affix our signatures.

HANS A. CHRISTIANSEN. [L.S.]
